ARTICLE OF JEWELRY

Joseph J. Franklin, Jr., Orange, N. J.

Application June 14, 1934, Serial No. 730,660

11 Claims. (Cl. 24—206)

This invention is directed to an improvement in an article of jewelry designed for use in either a ring or bracelet and having capability of simple and convenient adjustment for varying its size 5 in use.

The primary object of the invention is the provision of a selected number of sections of the article which are constructed with a view to permitting more or less permanent variation in the 10 diametric size of the complete article, with such size-adjusting sections selectively capable of varying the diameter of the completed article and maintaining such variation at will. Thus, the article includes sections by which the size of 15 the article may be adjusted in diameter according to the desired size, with the adjustment selectively provided for in one or more places and capable of being varied in a simple, expeditious manner.

20 The invention is illustrated in the accompanying drawing, in which:

Figure 1 is a view in front elevation of the article, here shown as a finger ring.

Figure 2 is an edge view of the same.

25 Figure 3 is an enlarged broken longitudinal section of the ring.

Figure 4 is a perspective view illustrating the adjusting section in preferred form.

Figure 5 is an elevation of a modified form of 30 adjusting section.

Figure 6 is an elevation of a further modification of the adjusting section.

Figure 7 is an elevation of a further modification of the adjusting section.

35 The article forming the subject-matter of this invention, here shown as a ring, is made up of what may be termed ornamental sections 1, adjusting sections 2, and locking sections 3. These sections may be made in any desired external configuration and ornamentation. For example, the sections 1 may be made in skeleton outline of ornamental configuration, while the adjusting sections 2 may be formed or otherwise provided for the reception of precious stones or other ornamentation. The invention is not concerned with the character or degree of ornamentation and is mentioned merely to indicate the fact that the adjusting sections are peculiarly and particularly formed to accommodate gem-receiving recesses 50 or otherwise to receive precious stones.

The ornamental sections 1 as shown terminate at each end in a cross bar 4 which extends between the otherwise unconnected side bars 5. All of the sections 1, 2 and 3 are, of course, curved in longitudinal plane in order that together they

may form a ring-like body. The cross bar 4 is preferably, though not necessarily, of triangular form in cross section, the apex 6 or narrowest portion of the cross bar being toward the convex side, i. e. the outer side, of the section 1.

5 The adjusting section 2 is made up of a solid bar-like member 7, the width of which is substantially equal to the length of the free portion of the bar 4. The section 2 includes underlying integral sections 8 which are connected at their ends with the member 7 and which have free terminals 9 substantially meeting at the mid-length of and beneath the member 7.

The sections 8 are, through the ends 10 with which they are integrally connected with the member 7, of spring-like tendency, permitting the sections 8 to be moved away from the member 7 under pressure and to be returned into substantial contact with said member when relieved of pressure. The upper surface of each spring strip 10

15 8, that is the surface next the inner surface of the member 7, is formed with notches 11 which, of course, may be in appropriate or desired number, though normally two such notches in each spring strip will be sufficient.

20 Obviously, by mere displacement of either or both of the spring strips 8, the bar 4 may be seated in either notch 11 and when in the relatively remote notches 11, that is, the notches closest to the spring ends 10 of the sections 8, the maximum 25 extension adjustment is provided for, while with the bar 4 seated in any of the other notches in either or both of the spring strips 8, a less extended adjustment is provided for.

25 Where the bar 4 has been seated in one notch 30 and it is desired to move it to an adjacent notch, such adjustment is assisted by the wedge-shaped formation of the bar 4, as the apex 6 of such bar may be readily forced between the spring strip 8 and the bar 7 to displace the spring strip to the 40 extent to permit the bar to be moved from the outermost notch to the innermost notch.

35 In the form shown in Figure 5, the adjusting section 2' is made up of a solid bar-like member 45 12, the width of which is substantially equal to the length of the free portion of the bar 4. The section 2' includes longitudinally spaced notches 13 arranged at the respective ends and at the relatively inner side of the bar 12, and integral with the bar 12 through a neck 14 are spring strips 15 50 which extend in opposite directions from the neck and underlie and act as spring closures for the respective sets of notches 13. The application of the bar 4 to either of the notches 13 by displacement of the spring strip 15 or the transfer of the 55

bar 4 from one notch 15 to an adjacent notch assisted by the wedge-shaped formation of such bar, is obvious from the description in connection with the preferred form.

5 In the further form shown in Figure 6, the adjusting section, indicated at 16, is provided with a body portion 17 from which depends a neck 18, and under which body portion are arranged spring plates 19. In this modified form, the notches 20 10 are preferably formed in the spring plate. The operation of this form in connection with the adjustment of the diameter of the ring or bracelet is obvious from the above disclosure.

15 In Figure 7 there is shown a further modification in which the construction of the section is in accordance with the preferred form except that the notches are duplicated on the bar-like member and on the spring strips. In this form, the adjusting section is made up of a bar-like member 21 having underlying spring strips 22 connected at their ends 23 with the bar-like member, with the free terminals of the spring strips 22 meeting substantially at the mid-length of and beneath the bar-like member 21, the meeting ends 25 of the strips 22 presenting upturned sections 24. In this form the notches, which in the preferred form are provided on the spring strips, are as shown at 25 and 26 formed in both the bar-like member 21 and the spring strips 22, the notches 30 being formed, of course, on the adjacent faces of these parts and arranged to together form a recess for the reception of the cross-bar 4 of the ornamental sections 1. The operation of this modification is, of course, apparent from the description above in connection with the preferred form.

40 By the use of the adjusting section of either form, therefore, the diameter or size of the ring may be permanently adjusted within the limits permitted by the respective notches. It is understood, of course, that the invention is without limitation as to the number of adjusting sections that may be used, as it is contemplated that the adjusting sections in any one ring formation may 45 provide for a very considerable increase or decrease in the size of the ring, and such adjusting sections may, if desired, be used alternately with the ornamental sections, as illustrated in Figure 1.

50 This arrangement of using the adjusting sections alternately with the ornamental sections is particularly desirable where the adjusting sections are used as the means for receiving and positioning precious stones or other similar ornamentation to be applied to the ring, for it is quite obvious that with the adjusting sections used alternately with the ornamental sections, the size adjustment of the ring may be accomplished by manipulating one alone of the adjusting sections 55 or more than one, as may be desired.

60 It is to be further noted that the adjusting sections are preferably of increased thickness with respect to the ornamental sections, a provision which enhances the artistic value of the ring, particularly where the adjusting sections are used 65 for the reception of precious stones and the like, as under these circumstances the ornamental stones stand out beyond the surface of the ornamental sections, as will be obvious.

70 It is quite obvious that, if desired, all of the sections may be formed for the reception of precious stones or the like or such sections may be made plain or ornamented by engraving or otherwise constructed within the purview of this 75 invention. Furthermore, while it is preferred

that the adjusting sections alternate with the ornamental sections, this is not an actual necessity and one or more of the adjusting sections may be used, for it is quite apparent that the use of additional adjusting sections when considered solely from the standpoint of adjustment merely permit a greater variation in the more or less permanent size of the ring or other article.

5 What is claimed to be new is:

1. In a ring having ornamental sections each 10 with a terminal cross bar, an adjusting section formed at each end with a longitudinally ranging opening with each opening designed to receive the cross bar of an adjacent ornamental section, and projections carried by the adjusting section and normally dividing each opening into transverse channels, with the channels of each opening at respectively increasing distances from the free ends of the section, each projection being movable to permit the cross bar at that end of 20 the adjusting section to be moved from one channel to another to thereby vary the distance of the cross bar from the end of the adjusting section at will.

2. In a ring having ornamental sections each 25 with a terminal cross bar, an adjusting section formed at each end with longitudinally ranging openings of a size to receive and permit free sliding movement of the cross bar, the adjusting section including for each opening a projection 30 movable transverse the opening to divide the opening into a plurality of cross bar-receiving channels closed against each other for cross bar-receiving purposes while the projection defining said channels is in normal position, the projections being movable in a direction to establish communication between the channels to an extent to permit the cross bar to be moved from one channel to the other at will, whereby to position the cross bar of an ornamental section at a 40 selected distance from the free end of the adjusting section at will.

3. In a ring having ornamental sections each provided with a terminal cross bar, an adjusting section formed to provide longitudinally ranging 45 openings extending from each end of the section toward the center thereof, the openings being of a size to permit free movement of the cross bar therein, and projections carried by the adjusting section and movable into the openings to 50 divide the openings into transverse channels arranged at relatively different distances from the free ends of the adjusting section, the projections when in normal position preventing movement of the cross bar from one channel to the other, 55 the projections being movable relative to the adjusting section to an extent to permit the cross bar to be moved from one channel to an adjacent channel for adjustment purposes.

4. An adjusting section for rings comprising 60 two parts integrally united centrally to provide on opposite sides of such central point independent openings to receive the cross bars of adjacent ornamental sections of the ring, one of the parts of the adjusting section being formed 65 to present projections to divide each opening into a series of transverse channels, the parts being inherently constrained to a position in which the projections normally prevent movement of the cross bar of an adjacent 70 ornamental section from one channel to the other, one at least of said parts of the adjusting section being movable relative to the other to cause the channel-defining projections to be moved to a position to permit the cross bar in one channel 75

to be moved to an adjacent channel for adjustment purposes.

5. An adjusting section for rings, bracelets and the like, including a main bar and a plurality of 5 spring-connected underlying sections formed with notches, one end of each of said sections being integrally connected with the main bar.

10. An adjusting section for rings, bracelets and the like, including a main bar and a plurality of 10 spring-connected underlying sections formed with notches, one end of each of said sections being integrally connected with the center of the main bar.

15. An adjusting section for rings, bracelets and the like, including a main bar and a plurality of 15 spring-connected underlying sections formed with notches, one end of each of said sections being integrally connected with the ends of the main bar.

20. An adjusting section for rings, bracelets and the like, including a main bar, and a plurality of 20 spring-connected underlying sections formed with notches, the adjacent free ends of the spring

sections approximately underlying the center of the main bar.

9. An adjusting section for rings and the like, including a main bar, a plurality of spring bars integrally connected with the main bar, each of 5 the spring bars being formed with notches to provide with the main bar a plurality of transverse channels opening through the sides of the main bar.

10. An adjusting section for rings, bracelets and the like, including a main bar and a plurality of 10 spring bars integrally connected with the main bar, the under surface of the main bar being formed with notches to provide with the spring bars a plurality of channels transverse the main 15 bar and opening through the sides thereof.

11. An adjusting section for rings, bracelets and the like, including a main bar, and a plurality of 20 spring bars integrally connected to the main bar, the adjacent surfaces of the main bar and spring bars being formed with notches to together provide a series of channels transverse the main bar and opening through the sides thereof.
